UNITED STATES PATENT OFFICE.

LEANDER ALSTON CLAPP, OF THE UNITED STATES NAVY.

MATHEMATICAL INSTRUMENT.

No. 866,432.

Specification of Letters Patent.

Patented Sept. 17, 1907.

Application filed November 1, 1905. Serial No. 285,475.

To all whom it may concern:

Be it known that I, LEANDER ALSTON CLAPP, of the United States Navy, auxiliary service, a citizen of the United States, and a resident of the town of Avon, in 5 the county of Norfolk and State of Massachusetts, have invented a new and Improved Mathematical Instrument, of which the following is a full, clear, and exact description.

My invention relates to a mathematical instrument 10 for solving spherical triangles and similar work.

The principal object of the invention is to provide means for performing a wide variety of calculations and doing away with the use of logarithmic tables for this purpose.

15 The instrument may be said to afford means for providing a graphic solution of problems of the character indicated above.

With these objects in view, I construct a device having a plurality of members adjustably connected together, each member being adapted to represent an element of a spherical triangle or other geometrical figure to be solved.

Reference is to be had to the accompanying drawings forming a part of this specification, in which similar 20 characters of reference indicate corresponding parts in all the figures.

Figure 1 is a front elevation partly broken away, of 25 an instrument constructed in accordance with the principle of my invention; Fig. 2 is a vertical central sectional view of the same, certain parts being in different position and certain parts being removed; Fig. 3 is a plan of a portion of the device with parts broken away; Fig. 4 is a plan of an attachment which can be applied to the main part of the instrument; Fig. 30 35 5 is a fragmentary sectional view of a portion of the instrument, showing the application of the attachment illustrated in Fig. 4; and Fig. 6 is a plan of a detail. Fig. 7 is a diagrammatic representation of the arrangement of the apparatus.

40 The main part of the instrument comprises three elements,—two limbs *a* and *b*, and a curved bar *c*. The two limbs *a* and *b* are in the form of a pair of flat frames pivotally connected together by means of a hinge *d*. These two frames are provided with circular scales *a'* and *b'* respectively. These two scales constitute the 45 edges of the frames and are drawn on an arc from the center of the hinge by means of which the two frames are connected. They are designed to represent two great circles. Rigidly mounted upon one of the frames 50 is a curved bar *e*, which passes through an opening in the other frame and is formed on a circle having the axis of the hinge *d* as its center. It will be obvious that the frames *a* and *b* can be swung about the hinge, being steadied and guided by the curved bar *e*, and 55 that either the scale *a'* or *b'* moving toward the other will describe an arc of a great circle at its center. Con-

sequently, if we suppose that the frame *b* moves toward or from the frame *a*, the scale *b'* will describe a portion of the surface of a sphere. In order to provide for this motion and to accurately adjust the angular position of the frame *b* with respect to the frame *a*, a projection *b*² 60 is mounted on the frame *b*, and is perforated to allow the passage of the bar *e*. The tubular member *e'* is mounted to slide on the bar *e*, and is adapted to be secured to it by a set-screw *e*². An adjusting screw *e*³ is 65 provided, making accurate adjustments between these two members. The bar *e* is scaled, and a vernier is preferably provided for the purpose of accurate reading.

On the scale *b'* is placed a vernier *f*, which is adapted to be adjusted by means of a screw *g* along the scale. 70 The scale *a'* is also provided with a vernier *h* mounted on a bracket *h'* and adapted to be operated by an adjusting screw *h*². The bracket *h'* is provided with an extension *h*³ adapted to be secured to the bracket by screws *h*⁴. This extension is spaced from the bracket 75 so that a ball *k* can be secured between these two parts, this ball constituting a universal joint for the bar *c*. This bar is provided with a scale, and with means for registering with the scale *b'*, said means being shown in the form of a rider *m*. This rider is provided with 80 projections *m'* adapted to engage in slots *o* in a plate *o'* located on the upper side of the bar. It is also provided with a set-screw *o*² for holding it in position, and with a point *o*³ for registering with the scale *b'*. It will also be seen that in addition to the adjustments of 85 the frame *a* and *b* the bar *c* can be placed not only parallel with the bar *e* but at an angle thereto, so that a complete spherical triangle is represented by the several members described.

For the purpose of showing the angle between the 90 bar *c* and the scale *b'*, or between the bar *c* and the scale *a'*, I provide an attachment, shown in Figs. 1, 4 and 5, to be substituted for the rider *m*. The plate *o* is used as before, and to it is secured a semi-circular convex disk *p*. This disk is provided with a scale 95 about its edge, and with a straight edge *p'* adapted to register with the center line of the bar *c*. It is also provided with a screw *p*² for holding it in position, and with a nut *p*³ fitting the screw and holding a pointer *p*⁴ thereon. In the use of this attachment the line 100 *p'* is placed parallel or coinciding with the center of the bar *c*, and the pointer *p*⁴ is moved to a position parallel with the scale *a'* or *b'*, as the case may be. This pointer then indicates the angle between the two elements on the scale located on the disk.

105 An instrument constructed in accordance with the principles set forth above provides means for representing all of the different parts of a spherical triangle, consequently, with the necessary number of parts known, the unknown functions can be obtained by 110 reading directly upon the several scales described. It is especially valuable for making calculations used

in navigation and it will not be necessary to describe the different problems which can be solved by its use. One example will suffice:

To find the true azimuth, set the instrument with 5 the hour-angle reading on the scale located on the bar e , the latitude on the scale b' , the declination on the scale a' . Swing the rod c so that the pointer o^3 is directly opposite the indicated latitude on the scale b' , then apply the azimuth attachment to the top of 10 the plate o' and swing the arm p^4 parallel to the scale b' , the line p' being parallel with the center of the bar c . This pointer will then register the true azimuth on the semi-circular scale. By the hour angle is understood the elevation of the object at the time at which 15 the observation is taken.

If it is desired to find the hour angle of any heavenly body, that is, the time that the body is from the meridian, observations are taken and the declination of that body north or south of the equator is marked on 20 the scale a' by moving the support for the rod c the proper distance to the right or left of the center. The observed altitude of the heavenly body as determined is marked on the rod c by moving the pointer o^3 along said rod for the proper distance. The north or south 25 latitude of the place at which the observations are taken is set off on the scale b' by moving the vernier f to the right or left of the center for the proper distance. The scales a and b are then moved relatively to each other on the hinge d and the rod c is moved 30 on its universal joint until the pointer o^3 carried by said rod may be brought into engagement with the proper point on the vernier f . By placing the attachment p over the universal joint of the rod c , the angle between said rod and the scale a may be read, and 35 this angle is the hour angle or time. If it is desired to determine the azimuth, the attachment p may be applied over the pointer o^3 and by moving the pointer f^4 into the same plane as the scale b' , the angle between said pointer and the scale may be read and 40 the azimuth thus determined.

In general the same parts of the instrument are usually employed to indicate the quantities represented in the above example, but this is not absolutely necessary in all cases. When used for such 45 calculations as this the instrument saves about three-quarters of the time and labor at present used in calculations for navigation. The hour-angle can be computed in less than a half a minute, rendering it especially valuable to fast steamships and all crafts 50 where observations are taken. For the student it illustrates the principle of these calculations in a graphic and clear manner, while it makes all calculations for the man who knows little of navigation, without requiring any great expenditure of time. 55 The use of the instrument can be learned by a person unskilled in mathematics, in much less time than the use of logarithmic tables. Furthermore, when logarithmic calculations are employed, a mistake is very difficult to find, and much time is necessarily 60 consumed when calculations do not result correctly.

With this instrument it is not easy to make a mistake, and if one should be made it would be seen at a glance.

The instrument may be supported in any desired manner and I have not illustrated any particular support. The various movable elements may also be 65 provided with handles for convenience in operation, and the verniers preferably have magnifying glasses.

Having thus described my invention, I claim as new and desire to secure by Letters Patent:

1. A mathematical instrument, comprising a pair of 70 frames pivoted together, a curved scale on each frame, means for adjusting the frames toward and from each other about their pivots, a bracket adjustable along one of said scales, and a scaled bar connected with said bracket by a universal joint. 75

2. A mathematical instrument, comprising a frame having a semi-circular scale thereon, a bracket adjustable along said scale, a curved bar connected with said bracket by a universal joint, and a frame adjustably connected with the first frame and having a semi-circular scale 80 thereon.

3. A mathematical instrument comprising a pair of frames pivoted together upon a central line, each frame having a semicircular scale drawn upon said line as a diameter, means for adjusting the frames at varying angles 85 with respect to each other, and a curved graduated bar adjustably secured to one of said frames and having a pointer adjustable thereon, said pointer being adapted to co-operate with the scale upon the other frame, as and for the purpose set forth. 90

4. A mathematical instrument, comprising a pair of frames pivoted together upon a central line, a semi-circular scale on each frame drawn upon said line as a diameter, a curved bar secured to one of said frames and drawn on an arc with said line as a center, the other frame being 95 provided with a perforation for receiving said bar, and means for adjusting the second frame along said bar; said means comprising a slide adapted to be secured to the bar in any position, and a screw connected with said slide and with the second frame. 100

5. A mathematical instrument, comprising a frame having a semi-circular scale thereon, a bar curved on an arc drawn from the center of said semi-circular scale, a universal joint for connecting said bar with said frame, and an attachment for said bar comprising a plate having an 105 edge adapted to coincide with the center of said bar and a semi-circular scale for indicating the angle between said bar and any other part of the instrument.

6. A mathematical instrument comprising a frame having a semicircular scale thereon, a bar curved on an arc 110 drawn from the center of said semicircular scale, a universal joint for connecting said bar with the frame, and means on the bar for registering with the scale.

7. A mathematical instrument comprising a frame having a scale thereon, a bar, means for movably connecting 115 the bar with said frame, and an attachment for said bar comprising a plate having an edge adapted to coincide with the center of the bar, a scale for indicating the angle between said bar and any other part of the instrument.

8. A mathematical instrument comprising a pair of 120 frames pivoted together, each frame having a scale, a curved bar secured to one of said frames, and means for adjusting the second frame along said bar, said means comprising a slide adapted to be secured to the bar in any position, and a screw connected with said slide and with the 125 second frame.

In testimony whereof I have signed my name to this specification in the presence of two subscribing witnesses.
